[57] CLAIM

The ornamental design for a child seat, as shown.

DESCRIPTION

FIG. 1 is a front view of the expanded child seat;
FIG. 2 is a rear view of the expanded child seat;
FIG. 3 is a top-plan view of the expanded child seat and
illustrates a seat for supporting a person and leg holes;
FIG. 4 is a bottom-plan view of the child seat and illus-
trates a seat for supporting a person and leg holes; and,
FIG. 5 is a side-elevational view of the child seat and
illustrates the strap for holding a person in the child seat
and illustrates a seat for supporting a person and leg
holes for the legs of the person.
